UNITED STATES PATENT OFFICE.

HARRY V. GOMPF, OF SPRINGFIELD, OHIO, ASSIGNOR, BY DIRECT AND MESNE ASSIGNMENTS, OF ONE-THIRD TO CHARLES S. JUDSON, OF SPRINGFIELD, OHIO, AND ONE-THIRD TO GOLDEN C. DAVIS, OF SPRINGFIELD, OHIO.

STRAINER FOR LIQUID FUEL.

Application filed September 14, 1922. Serial No. 588,198.

To all whom it may concern:

Be it known that I, HARRY V. GOMPF, a citizen of the United States, residing at Springfield, in the county of Clark and State of Ohio, have invented certain new and useful Improvements in Strainers for Liquid Fuel, of which the following is a specification.

This invention relates to strainers for liquid, it relating particularly to strainers for straining gasoline or other liquid fuel for internal combustion engines and has been designed especially for use in connection with the well-known vacuum feed system in common use on automobiles.

An object of the invention is to provide a novel arrangement for separating the sediment from the fuel before the fuel leaves the strainer.

20 A further object of the invention is to devise a strainer of the character referred to which will be simple in construction, economical in manufacture and effective in operation.

25 In the accompanying drawings:

Fig. 1 is a side view showing a portion of a well-known vacuum feed system with my improved strainer applied thereto.

30 Fig. 2 is a top plan view of the strainer. Fig. 3 is a side view looking at the device in a direction at right-angles to that as viewed in Fig. 1.

Fig. 4 is a section on the line 4—4 of Fig. 2.

35 Fig. 5 is a section on the line 5—5 of Fig. 3.

Fig. 6 is a section on the line 6—6 of Fig. 2.

40 Referring to the drawings, 1 represents the outer casing of a vacuum feed system of a well-known construction by which fuel is drawn from a storage tank by a vacuum created by the engine suction and fed to the carbureter. The cover thereof has an 45 interiorly threaded boss 2 to which the pipe from the fuel supply tank is ordinarily connected. In the present case this threaded boss is utilized for the purpose of attaching my improved strainer now to be 50 described.

There is provided a receptacle 3 which may be of any suitable material but is shown in the present case as made of glass. The top of this receptacle is closed by a

55 metallic cap 4 in such a manner as to exclude air at the joint. A simple form of clamping device is employed consisting of a wire 5 the ends of which are hooked together as indicated at 6 and two points of which are formed with loops 7 to receive bolts 8 which project through diametrically opposite ears 9 on the cap and receive nuts 10 by which the wire ring 5 may be drawn up the flaring sides of the glass receptacle and thereby tightened so 60 as to firmly clamp the upper edge of the same against a gasket 11 placed in an annular groove 12 on the under side of the cap.

65 The outer side of the cap is formed with an enlargement 13 projecting from a point near the center thereof to a point slightly beyond one edge and this enlargement is formed with a bore 14, the inner end of which communicates with a vertical bore 70 15 which receives a hollow stem 16. The outer end of the enlargement 13 is formed with an integral collar 17 to receive a connector by which the straining device is connected to and supported by the cover of the 75 casing 1. This connector is shown in detail in Fig. 6 and consists of a head 18 having an annular flange 19 and a hollow stem 20. The lower end of the hollow stem is exteriorly threaded so as to be secured into the threaded boss 2 to clamp the collar 17 between the flange 19 and the upper surface of the boss. The intermediate portion of the stem 20 is a smaller diameter than the interior of the collar 17 so as to provide a space in the collar about the stem and the stem is provided with a plurality of lateral openings 21 leading to the hollow interior thereof.

80 The cap 4 also has a second enlargement 23 open at its outer end and having internal screw-threads 24 to receive any suitable form of coupling by which the pipe (not shown) leading from the supply tank is connected. The enlargement 22 also has a 85 vertical bore 25 in which is secured a downwardly extending hollow tube 26 having a goose neck 27 at its lower end so that the discharge end of the tube projects upwardly in a substantial central position in the 90 receptacle 3.

95 Connected to the extreme lower end of the tube 16, which is substantially in line with

the discharge end of the tube 27, is a disk 28 having a downwardly projecting annular flange 29. Also secured to the tube 16 at a point above the disk 28 is a similar disk 30 having a similar flange 31, the lower edge of which cooperates with the disk 28 to provide a comparatively narrow annular passageway 32 leading to the space between the disks. The tube 16 at a point therein located between the disks is provided with a pair of orifices 33 communicating with the interior of the tube, these orifices being located in the lower portion of the space between the disks.

15 The receptacle 3 is preferably partly filled with water, the water being maintained at a point slightly above the discharge end of the tube 26, which is preferably located substantially at the highest liquid level in 20 the outer casing of the vacuum system. Upon each creation of a partial vacuum in the inner chamber of the vacuum feed system a similar vacuum will be created in the receptacle 3 which causes a jet of fuel mixed 25 more or less with water to be projected against the under side of the disk 28 which acts as a deflector or baffle to project the fuel and water downwardly. This, it has been discovered, has the effect of separating 30 the sediment and other foreign particles from the liquid and causing it to be deposited in the bottom of the receptacle, and, when water is used, also has the result of separating the water from the liquid fuel by 35 holding the water back, but permitting the liquid fuel which is lighter than the water to rise in the receptacle to a point somewhat beyond the contracted annular opening 32 where it finds its way between the disks and 40 into the tube 16 and from thence to the vacuum system through the connections before described. The liquid fuel in practice rises to a point somewhat higher than the disk 30, the fuel rising until the air in the 45 receptacle is compressed in the upper portion thereof sufficiently to stop the flow of the fuel beyond the quantity necessary to supply the demand of the system.

50 As the liquid fuel flows into the receptacle it also acts to compress the air in the chamber formed by the disk 30 and its flange 31, which, seeking to escape, flows into the receptacle through the liquid fuel entering the chamber through the narrow passageway 55 formed by the disk 28 and the lower edge of the flange 31 thus holding back any small particles of foreign matter in the liquid fuel and effectively preventing such particles from entering the orifice 33 of the tube 16.

60 When the vacuum is broken in the vacuum feed system air rushes into the receptacle through the orifice 33 with considerable force, dislodging any particles of foreign matter which have been deposited on the disk about 65 the orifice permitting the foreign matter to

settle to the bottom of the receptacle. The head of the liquid at this time drops rapidly in the receptacle, which also acts to wash from the disks particles of dirt, or other foreign matter.

70 When a partial vacuum is created liquid fuel flows into the receptacle and after it rises above the orifice 33 the remaining air is compressed, forming an air pressure in the top of the receptacle which acts in conjunction with the lower baffle plate to prevent to a large extent agitation of the liquid fuel in the receptacle, thus preventing the sediment in the bottom of the receptacle from rising to the top of the liquid.

75 The effect of this construction and operation is to cause the sediment in the liquid fuel to be separated therefrom, the water acting as a separating medium and also serving to hold the sediment in solution therein, the sediment accumulating in bottom of the receptacle which may be readily removed and cleaned when necessary. This device has been found in practice to be very effective 80 for the purpose for which it is designed and not only eliminates the sediment from the fuel but the peculiar construction thereof also effectively prevents the water from entering the feed system.

85 While, as before stated, water is preferably employed in the receptacle to assist in the separation of the sediment, it has been found that very good results in the separation of the sediment can be secured without the use of water, and it has also been found that 90 the peculiar arrangement of parts has the effect of separating any water which may be in the fuel and causing it to be deposited in the bottom of the receptacle.

95 Having thus described my invention, I claim:

1. In a device of the character described, a receptacle, means for supplying liquid fuel to said receptacle, a connection to a vacuum feed system having a portion thereof projecting into said receptacle and having a communication with the interior thereof, and a chamber arranged about the entrance from said receptacle to said connection having an air space above said entrance, for the purpose specified.

100 2. In a device of the character described, a receptacle, means for supplying liquid fuel to said receptacle, a connection to a vacuum feed system having a tube projecting into said receptacle and communicating therewith, and a chamber arranged about the entrance to said tube from said chamber having an air space above said entrance, for the purpose specified.

105 3. In a device of the character described, a receptacle, means for supplying liquid fuel to said receptacle, a connection to a vacuum feed system having a tube located in said receptacle, said tube having an orifice form-

ing a communication between the interior of said tube and said receptacle, a pair of disks connected with said tube on opposite sides of said orifice, the upper disk having a 5 down-turned peripheral flange to form an air chamber above said orifice and also to cooperate with the lower disk to form a restricted entrance for the fuel, for the purpose specified.

10 4. In a device of the character described, a receptacle, means for supplying liquid fuel to said receptacle, a connection to a vacuum feed system leading from said receptacle from a point above the inlet of said sup- 15 ply means, and a chamber surrounding the entrance from said receptacle to said connection, said chamber having an air space above said entrance and also having a comparatively narrow peripheral passageway 20 leading from said receptacle thereto.

5. In a device of the character described, a receptacle, a liquid fuel supply tube projecting into said receptacle and discharging upwardly, a second tube leading from said 25 receptacle to a vacuum feed system, the inlet of said second tube being located above the discharge end of said first tube, and a chamber surrounding the inlet to said second tube and having an air space above said inlet, 30 said chamber also having a fuel inlet from said receptacle.

6. In a device of the character described, a liquid fuel supply tube projecting into the lower portion of said receptacle, a second tube leading from said receptacle to 35 a vacuum feed system, the inlet to said second tube being located above the discharge end of said first tube, a pair of disks connected with said second tube on opposite 40 sides of said inlet, the upper one of said disks being provided with a down-turned peripheral flange to form an air space above said inlet and to also cooperate with the lower disk to form a peripherally extend- 45 ing fuel inlet to said chamber.

7. In a device of the character described, a receptacle, means for supplying liquid fuel to said receptacle, a connection to a vacuum system consisting of a tube projecting down-

wardly into said receptacle, said tube having 50 a lateral orifice communicating with the interior of said receptacle, and a pair of horizontally-disposed disks arranged in parallel spaced relation in comparatively close proximity to each other, one above and one below 55 said orifice, to form a restricted passage-way leading to said orifice.

8. In a device of the character described, a receptacle, means for supplying liquid fuel to said receptacle, and a tube extending 60 downwardly into said receptacle and having a communication with a vacuum feed system, said tube having an opening communicating with the interior of said receptacle at a point removed from the upper end of 65 said receptacle whereby the upper portion of said receptacle above said tube opening forms an air chamber in which air is compressed by the incoming liquid fuel.

9. In a device of the character described, 70 a receptacle, a tube extending downwardly into said receptacle and having a communication with a vacuum feed system, said tube having an opening communicating with the interior of said receptacle at a point removed from the upper end thereof, horizontally-disposed disks in parallel spaced relation arranged one on each side of said opening, and means for supplying liquid fuel to said receptacle at a point below the 75 said opening and disks, that portion of the receptacle above said opening and disks forming a chamber in which air is compressed by the incoming fuel.

10. In a device of the character described, 80 a receptacle, a liquid supply tube extending into said receptacle having a vertically-projecting discharge portion, a diaphragm above the discharge end of said tube and centrally over the same, said diaphragm 85 having a down-turned peripheral flange, and a connection between said receptacle and a vacuum feed system, said connection being arranged to take the liquid from said receptacle at a point above said diaphragm. 90

In testimony whereof, have hereunto set my hand this 23rd day of August, 1922.

HARRY V. GOMPF.
